CARTON FOR WAX RECORDS

Robert E. Worden, Fairfield, Conn., assignor to
 Dictaphone Corporation, New York, N. Y., a
 corporation of New York

Application April 28, 1938, Serial No. 204,784

2 Claims. (Cl. 206—15)

The present invention relates to an improvement in cartons for wax records or the like and more particularly to the bottom construction thereof.

Owing to the fragile character of wax records such as are commonly used on dictating machines or the like, it is desirable to protect them against chipping and cracking in use and in transit. Accordingly, cartons heretofore used 5 close various expedients for this purpose. An 10 object of the present invention is to provide a carton having a resilient bottom construction which can be made economically and embodied in a more attractive appearing container than 15 those heretofore available for similar purposes.

Embodiments of this invention are shown in the drawing appended hereto and in which—

Figure 1 is a central longitudinal section showing a carton with one form of bottom construction;

Figure 2, a transverse section on the line 2—2 of Fig. 1;

Figure 3, a fragmentary view in central longitudinal section of a modified form;

Figure 4, a transverse section on the line 4—4 of Fig. 3;

Figure 5, a fragmentary view in central longitudinal section, showing a further modification; and

Figure 6, a transverse section on the line 6—6 of Fig. 5.

Referring to the drawing, the carton construction shown in Figs. 1 and 2 comprises an outer tubular wall 1, having its bottom edge rolled or crimped inwardly to form a seat 2. A closure disc 3 is mounted with its peripheral edge supported on the seat 2. An inner tubular wall 4 fits snugly within the outer wall 1 and with its lower edge bearing against edge portions of disc 3 to hold the latter in position on seat 2.

To protect the surface of a wax record when in position within the carton, a lining 5 of flannel or the like is mounted on a tubular insert 6 secured to the inner tubular wall in any suitable manner as for example by spots of glue 7.

The closure disc 3 is preferably made of an inherently resilient material such as vulcanized fiber and is stamped or cut in such a manner as to form the resilient or spring tabs 8 extending above the normal upper surface of disc 3. They are held in position by an interposed ring or the like 9, also of any suitable material, such as vulcanized fiber. In this case, the ring 9 may be of thinner material or more resilient than the disc 3 so as to provide an additional cushioning effect.

In use, a wax record or the like rests in the

carton with one end supported on the tabs 8 which by reason of their resiliency provide cushioning means to absorb shocks and thus protect the record from injury under normal conditions of use.

In the modification shown in Figs. 3 and 4, the material of disc 3 is cut at its periphery or punched to form tabs 10 which correspond in function to the tabs 8 in Figs. 1 and 2.

In the modification shown in Figs. 5 and 6, 10 the material of the disc 3 is cut or punched to form cushioning tabs 11 having their free ends bowed so that edge portions thereof, as 12, Fig. 6, are presented toward or rest upon the upper surface portions of disc 3 adjacent to the openings 15 formed by the punching or cutting.

The various constructions herein shown present effective and inexpensive shock-absorbing or cushioning constructions for the several purposes hereinabove indicated.

As various embodiments might be made in the construction herein described, all without departing from the scope of the invention, it is to be understood that all matter herein set forth or shown in the accompanying drawing is to be interpreted as illustrative and not in a limiting sense.

I claim—

1. A carton for wax sound records or the like comprising an outer wall having one end turned inwardly to form a seat, a bottom wall of resilient material having edge portions supported on said seat and an inner wall within said outer wall and having edge portions engaging said bottom wall to retain it on said seat, said bottom wall having cushioning portions in the form of tabs biased inwardly and having their free ends spaced from and overlying adjacent openings in said bottom wall, and means operating between the tabs and said openings to limit the extent of movement of said tabs toward said openings.

2. A carton for wax sound records or the like comprising an outer wall having one end turned inwardly to form a seat, a bottom wall of resilient material having edge portions supported on said seat and an inner wall within said outer wall and having edge portions engaging said bottom wall to retain it on said seat, said bottom wall having cushioning portions in the form of tabs biased inwardly and having their free ends spaced from and overlying adjacent openings in said bottom wall, said tabs being bowed to present edge portions of their free ends across said openings to engage portions of said bottom wall adjacent said openings to limit the extent of movement of said tabs toward the openings.
